UNITED STATES PATENT OFFICE.

GEORGE L. HOWELL, OF MUNGER, MICHIGAN.

ROTARY PUMP.

1,085,127.

Specification of Letters Patent. Patented Jan. 27, 1914.

Application filed February 11, 1913. Serial No. 747,633.

To all whom it may concern:

Be it known that I, GEORGE L. HOWELL, a citizen of the United States of America, residing at Munger, in the county of Bay 5 and State of Michigan, have invented certain new and useful Improvements in Rotary Pumps, of which the following is a specification, reference being had therein to the accompanying drawings.

10 The invention relates to rotary pumps more particularly designed for use in irrigation, and it is the object of the invention to obtain a construction which is efficient, may be constructed at small cost, and requires little repair.

To this end the invention consists in the construction as hereinafter set forth.

In the drawings: Figure 1 is a side elevation of the wheel. Fig. 2 is an elevation at 20 right angles to Fig. 1. Fig. 3 is a cross section through the periphery of the wheel showing the bucket construction.

A is a rotating shaft; B are spokes connecting the hub C with the rim D; E are 25 buckets secured to the rim D and which are open at one side; and F is a segmental plate which extends around a portion of the rim D and forms a cover plate for the open sides of the buckets. This plate is preferably 30 provided with flanges G and H for overlapping the outer and inner walls of the buckets, the outer flange G being of greater depth than the inner flange H. The wheel is preferably mounted in an inclined position 35 as shown in Fig. 2 and the plate F is arranged adjacent to the down-turned side and extends from the bottom to near the top of the wheel.

I is a chute or trough, which is adjacent 40 to the upper end of the plate F and is arranged to receive the water discharged from the buckets.

In operation, motion is communicated to the shaft A from any suitable source of 45 power and the wheel is driven in the direction of the arrow. The lower portion of the wheel, as for instance below the line J K, is beneath the surface of the lower water level, and consequently the buckets E will be filled 50 with liquid before passing into proximity to the plate F. As the wheel rotates these buckets will be carried around the plate F, which latter will retain the greater portion of the water therein, particularly where the 55 wheel is rotated at a relatively high velocity. The overlapping flanges G and H, while out

of contact with the buckets, are nevertheless sufficiently near to form a water packing which will reduce the leakage to a small amount. As soon as the buckets pass beyond 60 the upper end of the plate F they are free to discharge their contents laterally on to the chute I, and by reason of the inclined position of the wheel the water is rapidly discharged, so that the buckets are completely 65 emptied before passing beyond the chute I.

The construction just described is one capable of being operated at relatively high speed and the centrifugal force will therefore lessen the tendency to leakage around 70 the inner flange H. On the other hand, there will be an increased pressure of water at the joint between the outer flange G and the buckets. I therefore constructed the outer flange G of greater width than the 75 inner flange, as shown in Fig. 3.

What I claim as my invention is:

1. A rotary pump, comprising a rotating wheel, a series of relatively stationary buckets carried by the periphery of said wheel 80 and provided with an open side for discharging laterally or sidewise in relation to said wheel, a stationary segmental plate extending around a portion of the periphery of the wheel adjacent to said buckets and closing 85 the open side thereof.

2. A rotary pump, comprising a rotating wheel, a series of relatively stationary buckets carried by said wheel having open sides for lateral discharge, a segmental stationary 90 plate extending about a portion of said wheel adjacent to said buckets and closing the open sides thereof, and a flange at the edge of said plate overlapping the peripheral side of said buckets and forming a water 95 packing.

3. A rotary pump, comprising a wheel revoluble about an inclined axis, a series of relatively stationary buckets carried by the peripheral portion of said wheel, said buckets having open sides for lateral discharge, a stationary segmental plate extending around a portion of said wheel adjacent to 100 said buckets and closing the open sides thereof, flanges extending from opposite 105 sides of said plate overlapping said buckets and forming a water packing, and a trough or discharge chute at the upper termination of said plate for receiving the water laterally discharged from said buckets. 110

4. A rotary pump comprising a wheel, a series of buckets attached to the rim of said

wheel and having open sides for lateral discharge, each of said buckets having peripheral segmental inner and outer walls connected by a return bend, a stationary segmental plate extending around a portion of said wheel adjacent to said buckets and closing the open sides thereof, flanges at opposite edges of said plates overlapping said buckets and forming a water packing, and a trough or discharge chute at the termination of the

upper end of said plate for receiving the water successively discharged from said buckets.

In testimony whereof I affix my signature in presence of two witnesses.

GEORGE L. HOWELL.
